By Attorney # UNITED STATES PATENT OFFICE.

GUSTAVUS A. SCHLECHTER, OF READING, PENNSYLVANIA.

DESIGN FOR A BUTTON.

SPECIFICATION forming part of Design No. 25,768, dated July 14, 1896.

Application filed May 4, 1896. Serial No. 590,234. Term of patent 7 years.

To all whom it may concern:

Be it known that I, GUSTAVUS A. SCHLECHTER, a citizen of the United States, residing at Reading, in the county of Berks and State of Pennsylvania, have invented a new and original Design for Pins or Buttons; and I do hereby declare the following to be a full, clear, and exact description of the invention, such as will enable others skilled in the art to which it appertains to make and use the same.

This is a design for a pin or button.

In the accompanying drawings, Figure 1 is a face view of a pin or button, illustrating the essential features of my design. Fig. 2 is a cross-sectional view of a button made in accordance with my design.

The leading feature of the design is a rose with a heart and cross in the center thereof.

A is the pin or button, and b is a small heart located in the center thereof and enclosing a cross c. The heart forms the center of a five-petal rose d.

What I claim is—

The design for a pin or button, substantially as shown and described. 25

In testimony whereof I affix my signature in presence of two witnesses.

GUSTAVUS A. SCHLECHTER.
